A. PROBST

HANDKERCHIEF VENDING MACHINE

Filed Sept. 23, 1925

INVENTOR

Albert Probst.

UNITED STATES PATENT OFFICE.

ALBERT PROBST, OF LOS ANGELES, CALIFORNIA.

HANDKERCHIEF-VENDING MACHINE.

Application filed September 23, 1925. Serial No. 58,095.

My invention relates to improvements in vending machines and the objects of my improvement are, first, to provide a machine suitable for vending handkerchiefs, and second, to provide a mechanism therefor simple of construction and sure of operation. I accomplish these ends by the means illustrated in the accompanying drawings, in which—

Figure I is a front elevation of the whole device,

Figure II is a sectional elevation, side view,

Figure III is a plan view of the combined handle and slide,

Figure IV is a side view of the slide, and

Figure V is a plan view of the coin trigger.

The magazine 1 carries a stack of cartons, each holding a handkerchief. The bottom 20 carton 2 rests upon a slide which consists of a horizontal elevated portion 3, a lower horizontal portion 4, and a handle portion 5 which carries an aperture large enough to allow the cartons to fall through and which 25 projects beyond the front wall of the vending machine.

A spring 6 draws the handle back into the machine after the delivery of each carton. A coin chute 7 leads from the external coin 30 slot 8 diagonally down to the coin trigger 9.

An arm 10 of the slide 4 projects vertically downward, and by striking against a projection 11 on the coin trigger 9 prevents the drawing out of the handle, since said 35 projection 11 is in horizontal alinement with the point of fulcrum 14 of the coin trigger.

When, however, a coin drops from the chute 7 into the coin trigger 9, the weight of the coin overbalances that of the counterpoise 13 and the coin trigger drops to the 40 position indicated by the dotted lines. A pull on the handle 5 now withdraws the bottom carton from the stack, and the next carton above drops down upon the platform 3. At the same time the vertical arm 10 follows the projection 11 on the coin trigger 45 and pushes it back to the third position indicated by dotted lines, in which position the coin rolls out and drops into the bottom 50 compartment of the vending machine.

Since the platform 3 is elevated above the level of portion 4 by only about one half the width of a carton, any carton which falls upon it will always be low enough to prevent the return of a package which has been

pulled out into the forward compartment of the vending machine.

As the handle 5 is released, the spring 6 draws the slide back to its original position, whereupon the carton 2 drops thru the opening in the handle, the platform 3 slides out from under the next carton and it falls into the original position of carton 2, and the coin trigger 9 swings into its original position beneath the coin chute 7, and locks the 65 slide until another coin is inserted.

After dropping through the aperture in the handle, the package slides down to an external opening 17 at the bottom of the machine. A glass window 18 assures the customer that there is a supply of handkerchiefs in the vending machine, and also informs him as to the nature of the contents.

I claim:

1. A coin controlled locking means for a reciprocating ejector comprising a receptacle, a counterpoise for said receptacle, a lever arm connecting said receptacle and said counterpoise, said lever having a right angle bend between its point of fulcrum and said counterpoise so constructed as to prevent the lever from swinging clear over even though it should pass the vertical position, a reciprocating ejector adjacent to said receptacle, and a means on said ejector to engage an extension on said receptacle.

2. In a handkerchief vending machine, a coin controlled locking means for a reciprocating ejector comprising a coin receptacle, said coin receptacle having an extension, a reciprocating ejector adjacent to said receptacle and having a vertical arm to engage the extension upon said coin receptacle, a counterpoise for said receptacle sufficiently heavy to hold said receptacle in a horizontal position as long as said receptacle is empty, but permitting said receptacle to descend enough to loose said ejector upon the reception of a coin, but still not enough to discharge the coin, until the vertical arm upon said reciprocating ejector has followed the extension upon said coin receptacle and pushed said receptacle into such a tilted position as to cause the discharge of the coin, and a coin compartment beneath said receptacle.

In testimony whereof, I hereby affix my signature.

ALBERT PROBST.
